(57) **CLAIM**

The ornamental design for an artificial worm plastic bait, as shown and described.

DESCRIPTION

FIG. 1 is a perspective view of an artificial worm plastic bait showing the design.

FIG. 2 is a first plan view of the artificial worm plastic bait shown in FIG. 1.

FIG. 3 is a second plan view of the artificial worm plastic bait shown in FIG. 1.

FIG. 4 is a first elevation view of the artificial worm plastic bait shown in FIG. 1.

FIG. 5 is a second elevation view of the artificial worm plastic bait shown in FIG. 1.

FIG. 6 is a first side elevation view of the artificial worm plastic bait shown in FIG. 1; and,

FIG. 7 is a second side elevation view of the artificial worm plastic bait shown in FIG. 1.

The broken lines shown in the figures represent portions of the artificial worm plastic bait that form no part of the claimed design. The artificial worm plastic bait is shown with a symbolic break in its length. The appearance of any portion of the article between the break lines forms no part of the claimed design.
